A. J. PARK

RAIL CHAIR AND CLAMP

Filed May 2, 1924

WITNESS:

R. S. Wise

ATTORNEY

UNITED STATES PATENT OFFICE.

ANDREW J. PARK, OF PUEBLO, COLORADO.

RAIL CHAIR AND CLAMP.

Application filed May 2, 1924. Serial No. 710,654.

To all whom it may concern:

Be it known that I, ANDREW J. PARK, a citizen of the United States, residing at Pueblo, in the county of Pueblo and State of Colorado, have invented new and useful Improvements in Rail Chairs and Clamps, of which the following is a specification.

The object of this invention is to produce a combined chair and joint for railway rails comprising members connected to the rails and extending the entire length of the track, and wherein the joints between the rails and the members are broken so that a practically continuous rail is produced.

15 To the attainment of the foregoing, the invention consists in the improvement as hereinafter described and definitely claimed.

In the drawings:—

20 Figure 1 is a perspective view showing the improvement secured on the rails of a track and spiked to the ties therefor.

Figure 2 is a transverse sectional view through the improvement as applied to a rail.

25 In the drawings the rails of a railway track are indicated by the numeral 1, and the supporting ties therefor by the numeral 2. By reference to Figure 1 of the drawing it will be seen that my improvement is 30 designed to extend the entire length of the track and that the improvement is arranged on the rails in a manner whereby the joints of the elements constituting the same are broken, and likewise the said improvement 35 breaks the joints between the confronting ends of the rails, and consequently provides a rail plate and brace chair which affords a substantially continuous rail.

The improvement is preferably constructed 40 of sections equalling the length of the rails 1. The improvement contemplates members, each of which includes a base 3 channelled to receive the base of the rail therein. The base, on its outer edge is integrally formed with an inwardly disposed 45 angle flange 4 which rests on the top of the outer flange of the rails 1. From the flange 4 the improvement is provided with an up-standing plate 5 that terminates in a thickened head 6. The head underlies the head 50 of the rail 1, on the outer side of the said

55 rail. The base 3 is continued outwardly from its flange 5 and is provided with openings that receive therethrough spikes 7 that enter the ties 2. At the joints of the rails 1, 55 and at the joints of the sections constituting my improvement I arrange in the fishing spaces on the inner sides of the rails angle fish plates 8 and 9. The fish plates 9 which are arranged at the joints of the rails 60 1 are longer than the fish plates 8 which are arranged opposite the joints of my improvement, and through these fish plates there are passed the ordinary bolts which are engaged by the usual nuts. Four bolts are passed 65 through the fish plates 9, while two are passed through the fish plate 8, this number being deemed sufficient to connect the connecting ends of the improvement.

70 The inner flange of the base 3 of the improvement is notched at determined intervals, as indicated by the numeral 10. These notches provide for the passage of pinch bars beneath the flanges of the rails and to assist in the arrangement of the rails in the 75 improvement or the removal of the rails therefrom.

Having described the invention, I claim:—

80 In combination with the rails of a railway track, of a means for bracing and providing a substantially continuous rail, comprising members of a length approximately equaling the length of the rails, each of said members having a channelled base to receive 85 the base of the rails therein, an outer angle flange to contact with the flange of the rail, a plate projecting from the flange and terminating in a head to underlie the head of the rail, said members designed to have 90 their ends disposed opposite the confronting ends of the rails, fish plates in the inner fishing spaces of the rails bolted to the members at the confronting ends thereof and likewise bolted to the members at the confronting ends of the rails, spikes securing the members on the ties, and said members having their base portions on their inner sides notched, for the purpose set forth.

95 In testimony whereof I affix my signature.

ANDREW J. PARK.
